UNITED STATES PATENT OFFICE.

WILLIAM LENDER, OF ALLEGHENY, PENNSYLVANIA.

DESIGN FOR PLATE-GLASS.

SPECIFICATION forming part of Design No. 26,718, dated March 2, 1897.

Application filed December 21, 1896. Serial No. 616,541. Term of patent 14 years.

To all whom it may concern:

Be it known that I, WILLIAM LENDER, of Allegheny, in the county of Allegheny and State of Pennsylvania, have invented a new and original Design for Plate-Glass, of which the following is a full, clear, and exact description, reference being had to the accompanying drawings, forming part of this specification, in which—

10 Figure 1 is a front elevation of a section of plate-glass, showing my design; and Fig. 2 is an edge view of the same.

The design relates to the ornamentation of the edge portions of plate-glass; and its essential feature consists in such a section having a beveled edge provided with flutings having chipped or splintered surfaces. The surfaces of the flutings being somewhat rough

and broken up, a very peculiar brilliant effect is obtained, especially when looking at the 20 opposite face of the glass.

In the drawings, 2 represents a square section of plate-glass, having upon its rear face beveled edges provided with a series of flutings 3, having rough or splintered surfaces, 25 which give a new and distinctive appearance to the article.

I claim—

The design for plate-glass, substantially as shown and described. 30

In testimony whereof I have hereunto set my hand.

WILLIAM LENDER.
